UNITED STATES PATENT OFFICE

GEORGE B. EHRMANN, OF TROY, NEW YORK

KEYHOLE GUARD FOR LOCKS

Application filed May 28, 1928. Serial No. 281,340.

The present invention relates to improvements in key hole guards for locks or devices adapted to be inserted in a lock and to prevent the lock being picked or opened by unauthorized parties.

In particular, the present invention is designed for use with locks of the character commonly employed on safe deposit boxes, and such an embodiment of the invention is illustrated in the accompanying drawing and will be hereinafter described in some detail. It is frequently desirable, owing to the death of the renter, litigation, or other causes, to temporarily seal safe deposit boxes. The common practice is to apply to such a box an auxiliary lock, generally in the form of a small pad lock, but such means is unsightly and also somewhat difficult to attach and remove. According to the present invention, means are provided for sealing such boxes, or preventing the operation of the lock thereof which will be entirely concealed and which can only be removed by use of a particular and special form of implement.

In the accompanying drawing:

Figure 1 is a top view, partly broken away, of a lock such as commonly provided on safe deposit boxes, having an embodiment of the invention inserted therein.

Figure 2 is a perspective view illustrating one manner of withdrawing the filling block from the lock.

Figure 3 is a view of the filling block, detached, on an enlarged scale, one of the side walls being removed, and the locking parts shown in normal position.

Figure 4 is a view similar to Figure 3 showing the position of the locking dog when the implement for withdrawing the block from the lock is inserted therein.

Figure 5 is an elevation of the outer end of the filling block.

Figure 6 is a section substantially on the line 6-6 of Figure 3.

Figure 7 illustrates a slightly modified form of the invention.

Figure 8 is a section view substantially on the line 8-8 of Figure 7.

Referring to the drawing, in the several figures of which like reference characters des-

ignate corresponding parts, 1 indicates the casing of a lock such as commonly employed for safe deposit boxes, the same including a tubular neck 2 that extends through the front wall of the door of such a box and a key-way 3 to receive the preparing and individual keys commonly required to actuate locks of the character referred to.

As the present invention is adapted for use with locks of various characters, it has not been thought necessary to illustrate in detail any of the interior mechanism, and to be sufficient to merely state that the embodiment of the invention illustrated includes a filling block 4 which is of such dimensions that it can be received in the key-way 3, before referred to, and as shown in Figure 1, when in operative position is entirely within the body of the lock and out of sight.

The filling block 4 is preferably made of two pieces connected by suitable rivets 5 to provide an interior chamber within which is pivotally mounted a dog 6 which is adapted to rock about its pivot through a slot in the edge of the block. A spring 7, attached to the block and bearing upon the tail of the dog 6, normally maintains the dog in the position shown in Figures 1 and 3 where its forward end projects from the block 4 and behind a portion of the front wall of the lock casing 1 so that the block, after being inserted in the lock, can not be withdrawn until the dog 6 has been positively moved to shift the normally projecting portion thereof into the interior chamber of the block.

It will be seen that no special means is required to insert the block 4 into the lock as the inclined face or edge of the projecting portion of the dog will be moved into alignment with the edge of the block by contact with the wall of the neck 2 of the lock and as soon as the block has been inserted in the lock to the desired distance, said dog will automatically return to its normal position shown in Figures 1 and 3, and effectually prevent the block from being withdrawn until the dog is rocked to inoperative position.

Various means may be provided for rocking the dog from operative position to per-

mit of the block being withdrawn. In the drawing two different forms of means for this purpose are illustrated.

In the form shown in Figure 2, the block 4 is made of metal or provided at its outer end with a suitable portion of metal and a withdrawing implement is provided having a magnetic section 10 adapted to be inserted in the outer end of the key-way 3 and by magnetic action connect the block therewith so that the block can be withdrawn when the latch 6 is rendered inoperative. For this purpose the implement referred to is provided with an elongated pin 11 adapted to be inserted into the chamber in the block, through the passage 9 thereof that opens through the outer end of the block, so as to engage the tail of the dog 6 and rock the same into inoperative position as shown in Figure 4.

When the dog has thus been rendered inoperative, and the outer end of the block is held by magnetic action to the magnet section 10, it will be seen that the block can be readily withdrawn from the lock with the magnet member.

The magnet section 10 may be a permanent magnet, or as shown in Figure 2, may be an electro-magnet being attached to a core extending into a suitable casing 12 within which is arranged an electric coil 13 and a battery or dry cell 14. By manipulating a push button 15 carried by the casing 12 the magnet section 10 can be rendered operative at will.

As shown in Figure 5, the passage 9 leading from the chamber in the filling block through the outer end of the block is preferably made of substantially triangular form in cross section, and the pin 11 is of similar form, the relatively sharp edge thereof making the desired contact with the tail of the dog 6 when inserted in the filling block, as shown in Figure 4.

Instead of using a magnetic means for withdrawing the filling block from the lock, various forms of mechanical means may be employed. A more or less conventional illustration of means of this character is shown in Figures 7 and 8 in which the implement 16 for rendering the dog 6 inoperative and withdrawing the filling block is provided with a pin 17 that is of such diameter that it will operate on the tail of the latch to withdraw the same into the chamber in the block when said pin is fully inserted therein. Near its free end the pin is provided with a slightly reduced section 18 in which the tail end of the dog will be received when the tool is fully inserted into the position shown in Figure 7. Such an arrangement will act to maintain the dog in inoperative position within the filling block, and by an outward pull on the handle 16 the filling block may be bodily withdrawn from the lock. When withdrawn a slight relative rotary movement

between the plug and the pin will permit these parts to be disengaged and the latch or locking dog to be restored to its normal position by the spring 7. If desired, the pin 17 may be extended throughout the length of the member 16, and provided at its outer end with a head by which it can be rotated when withdrawn from the lock.

While, as before described, it is preferred to provide the filling block 4 with a retaining means, such as the dog 6, such dog might be omitted, and the filling block merely made of magnetizable material of such form and dimensions as to be inserted in the keyway, and when in position, entirely concealed, said block being withdrawn from the keyway by a suitable magnetic means, as described.

It is believed that the operation and advantages of the invention will be readily appreciated from the foregoing description in connection with the drawing.

It is to be understood, of course, that in the drawing, several of the parts are shown more or less conventionally, and there can of course be considerable variation in details without departing from the invention.

The invention provides a very simple and effective key hole guard for locks which is entirely concealed when in use and can only be withdrawn by the use of a special implement.

I claim:

A means for the purpose described, comprising a pin-like member, a magnet at one end of the pin, and a filling block which is freely movable lengthwise of the pin, whereby it may be positioned in the key way of a lock by the pin, and provided with a pivotally mounted dog adapted to be automatically projected therefrom to constitute an abutment preventing withdrawal of the block from the key way when the pin is withdrawn and which dog is moved into non-projecting relation to the block, as the pin is positioned in the block, prior to the magnet coming into operative relation to the block.

In testimony whereof I have hereunto set my hand.

GEORGE B. EHRMANN.
